UNITED STATES PATENT OFFICE.

FREDERICK H. BEHRING, OF ST. LOUIS, MISSOURI.

PLAYING-CARDS.

1,143,595.

Specification of Letters Patent. Patented June 15, 1915.

Application filed June 18, 1914. Serial No. 845,962.

To all whom it may concern:

Be it known that I, FREDERICK H. BEHRING, a citizen of the United States, residing at St. Louis, Missouri, have invented a certain new and useful Improvement in Playing-Cards, of which the following is a full, clear, and exact description, such as will enable others skilled in the art to which it appertains to make and use the same.

10 This invention relates to games of the class that are played with cards.

The main object of the invention is to provide a card game by which golf can be played with cards in practically the same 15 manner as golf is played on a golf links.

Another object is to provide an amusing indoor game which is instructive to the players, in that it teaches a person the essential features and rules of the game of golf, 20 namely, the description and uses of the principal clubs used in playing golf; the terms used in golf and the particular clubs that should be used for making certain plays in the field. And still another object is to 25 provide a deck of cards by which the game of golf can be played by as many persons as can play golf comfortably on a golf links.

The game is played with a deck of cards which is preferably divided into eight 30 groups, each of which represents one of the principal clubs used in the game of golf. The cards of each group have certain words, characters or other indicia on the face of same which indicate the strokes or shots 35 that are usually made with a club of the kind the card represents, and certain of the cards of each group are provided with means which represent penalties that result from unskilful use of the club represented by the 40 card, and also for restricting the player to the use of a certain club or clubs on the succeeding play or stroke.

A set of rules is provided for governing the play of the cards so as to familiarize the 45 players with the clubs that should be used for making certain plays on a golf links, and thus teach the game of golf to a beginner and also enable a golf player to perfect his game in playing on the links.

50 The object of the game is to cover the distance from the "tee" to the "hole" in the fewest number of strokes, each card that is played counting as a stroke.

In playing the game the cards are arranged in their respective groups and one 55 card from each group is dealt to each player, so that each player will have cards that represent the principal clubs used in playing golf, the deck of cards herein illustrated being divided into eight groups, representing 60 a driver, a brassy, a cleik, a mid-iron, a loftier, a mashy, a niblick and a putter. In starting the game the players match their driver cards so as to determine who has the "honor," or in other words, who has the 65 first drive from the starting "tee," the player whose driver card is of the greatest value, that is, of the highest value, or which represents the longest stroke, having the honor. The player whose driver card is of 70 the next greatest value plays second, the one whose driver card is of the next greatest value playing third, and so on, until each player has played his driver card. After the first play, or in other words, after each 75 player has played his driver card, the player whose driver card indicates the greatest distance from the "hole" plays next, the other players playing in turn, according to the distances their driver cards indicate they 80 are from the "hole." The player who reaches the "hole" in the fewest number of strokes (namely, cards played) wins the first "hole."

The cards of the various groups that are 85 not dealt to the players constitute "bone piles," from which the players draw cards under certain conditions.

After one "hole" has been played the cards of the different groups are collected 90 and shuffled, and thereafter dealt out to the players prior to starting for the second "hole."

The drawings comprise eight sheets, each of which relates to one of the eight groups 95 of cards constituting the deck of cards with which the game is played, and, in order to avoid confusion that might result if each card were treated as a separate view or figure of the drawings, I have treated each 100 group of cards as constituting one figure of the drawings. For example: Figure 1 illustrates the cards in the group that represent the driver; Fig. 2 those that represent the brassy; Fig. 3 those that represent 105 the cleik; Fig. 4 those that represent the mid-iron; Fig. 5 those that represent the loftier; Fig. 6 those that represent the mashy; Fig. 7 those that represent the niblick; and Fig. 8 those that represent the putter. The view at the upper left hand corner of each of said figures illustrates the back of the cards of that particular group and the other views of the figure illustrate the faces of the cards.

The complete deck preferably comprises one hundred and twenty cards, but certain 10 of the cards, which are duplicates, have been omitted from the drawings.

The driver cards shown in Fig. 1 have the word "Driver" or some other character, symbol or indicia 1 on the back of same that 15 defines said cards and tell what particular club the card represents. On the faces of said driver cards are words, symbols or characters 2 that designate the value of the cards and indicate strokes of varying distances that can be made with a driver when 20 playing a game of golf on a golf links, certain of the driver cards being duplicates or of the same value, but most of them having different values, running from 225 yards to 25 75 yards. Certain of the driver cards represent unskilful or unlucky strokes that are often made with a driver in playing the game of golf, as, for example, a stroke which sends the ball into the long grass, into 30 a "bunker" or "out of bounds", the value of such cards being designated by a means 2^a which preferably consists of characters designating the distance and the words "in long grass". A similar means 2 is used to 35 indicate the value of cards that represent strokes into a "grass hazard", into a "bunker" and "out of bounds". One of the driver cards is provided on its face with a means 2^b, preferably consisting of the 40 word "foozle", that determines the value of this card and designates a stroke at the ball which missed it, making it necessary to play again. Those driver cards that are provided with a means 2^a, which indicates an 45 unlucky or unskilful stroke, are also provided with a means 3 that restricts the player to the use of a certain club or card on the following play: For example, the driver card, whose value is "200 yards in long 50 grass", has the words "play loftier or niblick out", thus restricting the player of that particular card to the use of a loftier or niblick card on the succeeding play. In addition to the means 3 above mentioned indicating a 55 restriction in the use of a club on the succeeding play, certain of the cards that represent unlucky or unskilful strokes are provided with a means 4 that designates a penalty, such, for example, as a reduction in the 60 distance specified in the means 2^a that designates the value of the card, as, for example, the card which represents a stroke of "200 yards in long grass", is provided with a means 4 that preferably consists of the words "penalty 10 yards", which is deducted from the 200 yard stroke in determining the value of that particular card, thus giving a net value to the card of 190 yards. In other words, the driver cards have various indicia on the face of same that 70 defines the value of each card, and certain of the cards have indicia on the face of same that restricts the player to the use of certain cards on the succeeding stroke.

The brassy cards, illustrated in Fig. 2, 75 which represent strokes that can be made with the brassy, have similar indicia on the face of same, and the word "brassy" or some other suitable character or symbol on the back of same that defines the cards of 80 this group. The cards in the other groups are similar, except that the proper word, character or symbol is printed on the back of the cards to define same.

In addition to the deck of cards above described, a set of rules and description of the clubs and their uses is provided so as to enable a person to learn the essential features and characteristics of the game of golf, and also aid a golf player in remembering the 90 clubs that should be used for certain plays.

I will not herein specifically describe all that is embraced under the heading "Description of clubs and their uses", but will merely state that a brief description of each club, represented by the cards of the deck, is given, as well as the purpose for which the different clubs are generally used. For example, the driver is described as "a wooden club used from the "tee" to get the 100 longest possible initial distance." The brassy is described as being "similar to the driver, but has a brass sole and more loft (slant of face of club), to enable balls to be picked out of grass and elevated enough to get out and make good distance through the 'fair green'."

The following golf terms, with a brief description of same, is also provided so as to familiarize a novice with the terms generally used in the game of golf: "fore"; "tee"; "fair green"; putting green; "hole"; "out of bounds"; hazards; bunker; sand traps; "foozle"; pulled or sliced; topped ball; scuffed ball; the honor; stinie; match play; medal play; bogie; and par. The play of the game should be governed by the following rules, but I wish it to be understood that my invention is not limited to a game played in the exact manner defined in said rules, as various changes can be made in the rules and in the number of cards constituting the deck and in the indicia on the cards, without departing from the spirit of my invention:

The honor.

(1) In starting off at the first "tee", the honor (that is, who drives first), should be decided by matching the driver cards, the best drive securing the honor. After the first play, the player farthest from the hole must play next. After the first hole the winner of the hole will decide the honor for the next hole. In case of tie for the honor, it remains with the player having it at the first hole or the preceding hole.

Clubs to be used.

10 (2) The "driver" should be used to drive off the "tee," except where the distance to the hole is less than 185 yards, in which case the appropriate club should be used regardless of the result of the first shot.

15 Table of distance for different clubs.

(3) To lead beginners at the game the following table is given as a guide to the proper club to use for shots of a given distance: The driver should be used off the tee for 185 yards and over. The brassy through the fair green for distances 175 yards and over. The cleik through the fair green for distances 165 yards and over. The mid-iron 20 through the fair green for distances 150 yards and up to 165. The loftier through the fair green for distances 125 yards and up to 150. The mashy through the fair green for distances 125 yards and under. The niblick through the fair green for distances 75 yards and under (especially from hazards). The putter or putting cleik on the putting green. This table is provided for this game and if followed will prevent 35 "freak" scores. A club should always be played for distances called for by the table where the distance remaining to be played will permit, but must be played regardless of results, except that the choice of interchangeable clubs, per paragraph 4, may be resorted to.

Order in which clubs should be played.

(4) The clubs should be played as nearly 45 as possible in the order shown in this table where the distance will permit, the variations of the clubs and their interchangeable qualities being as follows: Brassy, cleik, and mid-iron for either of the others. 50 Loftier and mashy, one for the other. Mashy and niblick, one for the other for short shots.

Clubs and shots not permissible.

55 (5) For example, it would be decidedly unfair to use for an approach shot of 85 yards a poor brassy shot calling for "75 yards into grass hazard" when the natural and proper play for the distance would be 60 a mashy shot; or, substitute for a shot where a brassy for 200 yards is needed a mashy shot that calls for 125 yards just because the brassy calls for a bad stroke. Neither should be played a loftier from a hazard 65 when less than 125 yards remains to be played, even though the card calls for "loftier or niblick" to be played, as the loftier from a hazard should be subject to the same distance as through the fair green as called for in the table of distances; nor 70 could a niblick, mashy or loftier "on the green" shot be played for a distance greater than the table allows for these clubs.

When a club is not playable, drawing card without penalty. 75

(6) Where a card for the proper club is to be played for the remaining distance calls for twice or more than the distance necessary to reach the putting green (circle extending twenty yards from the hole) it will not be obligatory to play it and the player can draw on the proper "bone pile" for that club without penalty. This rule also applies to the putter on the putting green, 80 the object of this rule being to prevent wild plays which would not happen in an ordinary game of golf, as the average player will not send the ball as far over the hole as he is away from it. 85

Cards must not be drawn from the "bone pile" when an interchangeable club card is held, which might be played without the foregoing injunction applying thereto. 90

Size of greens or when you are on the green. 95

(7) All putting greens will be considered the regulation size, a circle extending 20 yards from the hole so that a ball on the edge of the green is 20 yards from the hole, 100 even though it be 20 yards beyond the hole.

When ball is holed. Where the total of the shots to the green total the distance to the hole. 105

(8) The ball is holed when the total distance of the strokes through the fair green added together equals the exact distance shown by the score card for the hole, provided the ball is holed by the putter; for 110 example, where a good drive and mid-iron shot total the same as the distance desired, the ball will be counted on the green opposite the hole and the putt will be considered as holding out and completing the score 115 of that hole.

Sliced or pulled ball on or near green.

(9) Where the shot approaching the green is "sliced" or "pulled" and yet the 120 total of the plays equal the distance to the green or the distance of the hole, the ball will be considered as far off the green as the penalty (10 yards) for slicing or pulling calls for, making the ball lie 30 yards 125 from the hole.

When a hazard is not applied.

(10) When an approach shot that would land you on the putting green (within 20 130 yards of the hole) calls for a hazard, the hazard will be ignored, for the reason that there are no hazards on the putting green.

When duplicate cards may be drawn.

5 (11) When playing long holes and a second brassy shot is desired the player can draw a brassy card if the other interchangeable clubs (cleik or mid-iron) cards have 10 been played and enough distance remains for a brassy shot.

Penalty strokes.

15 (12) When a card in hand to be played indicates the club to be played next, the player must follow out the shot with the club card indicated regardless of results, except as provided, otherwise in rule 5. Where 20 two clubs are allowed either may be used by the player. In case both cards have been played and it is necessary to draw one or the other, the player can choose the club he will draw from the "bone pile." There is no penalty for drawing from the "bone 25 pile" unplayable cards; the penalty is attached to the cards that are played and each card played counts a stroke plus any penalty strokes a card may call for.

30 Bunker shots.

35 (13) "Back into bunker" is not playable if the shot is not being made from a bunker. The player will be allowed to draw another card of the same club until play can be made without penalty.

Cards.

40 (14) Cards should be shuffled after each hole is played and the different clubs carried in separate stacks in order of play. Time will be saved by the opponents shuffling and dealing the cards nearest them to their opponents.

45 (15) After dealing the players in the game one card per player from each stack, beginning with the driver, the remaining cards become the bone piles for their respective clubs to be drawn from in case the player is required to play another shot of a club already played. There are fifteen 50 cards for each club, covering practically all of the possible shots of the different clubs.

In order that the method of playing the game may be clearly understood, I give the following sample play, under the above-mentioned rules: For a 385 "hole" with a bogey of 5 and par. 4, the play would ordinarily be a driver shot, brassy or mid-iron shot, mashy or niblick and putter on the green. Say the cards are drawn as follows: 55 Driver—175 yards, sliced or pulled in long grass—net 165 yards. (Play loft or niblick out of long grass). Brassy—200 yards, sliced or pulled into long grass—net, 190 yards. (Play loft or niblick out of long 60 grass.) Cleik—175 yards. Mid-iron—165 yards. Loft—100 yards into bunker or sand trap. (Play niblick out.) Mashy—75 yards into ditch. Lift ball, count stroke and play mashy.) Niblick—75 yards. Putter—"Into the hole." You would, under the 70 starting rule, play (1st) the driver for 165 yards. This leaves 220 yards to make. The card penalizes you to "Use loft or niblick out of long grass." You have the choice in playing out of the hazard. (2nd) Play 75 niblick for 75 yards. This leaves 145 yards to make. (3rd) Play calls for mid-iron for 165 yards. This puts you on the edge of the putting green beyond the hole 20 yards. (4th) Play putter, which calls for "into 80 the hole," making a total of four (4) strokes. The temptation in playing would be to play the loft for 100 yards for immediate gain of distance for the second play, whereas the mid-iron following the niblick 85 saves a stroke.

Your partner draws the following: Drive, 175 yards. Brassy, 175 yards. Mashy, 35 yards, total 385 yards (same as distance of hole). Putt—for four (4) strokes—practically perfect shots.

Having thus described my invention, what I claim is:

1. A deck of cards, comprising a plurality of groups of cards, each of which group represents a different kind of golf club, said cards being provided with means that gives the cards different valuations.

2. A deck of cards, comprising a plurality of groups of cards, each of which group represents a different kind of golf club, the cards of the various groups having indicia thereon that designates strokes that can be made with golf clubs.

3. A deck of cards, comprising a number 105 of separate and distinct groups of cards that represent different kinds of golf clubs, the cards of each group having indicia thereon that designate good strokes and unskilful strokes that can be made with a golf club 110 of the kind that the card represents.

4. A deck of cards divided into a plurality of separate and distinct groups, each of which relates to a different kind of golf club, certain of the cards of each group 115 having indicia thereon which restricts the player of the card to the use or play of a certain card on his succeeding turn.

5. A deck of cards, comprising a plurality of groups of cards, each group of which is provided with means for indicating that the cards in said group represent a certain kind of golf club, and means on the cards of the various groups for designating strokes that can be made with golf clubs.

6. A deck of cards, comprising a plurality of groups of cards, each group of which is provided with means for indicating that the cards in said group represent a certain kind of golf club, and means on the cards 130 of the various groups for designating strokes that can be made with golf clubs, certain of the cards of each group having means that designate penalties which result 5 from unskilful or unlucky use of a golf club of the kind represented by the card.

7. A deck of cards, comprising a plurality of groups of cards, each group of which is provided with means for indicating that 10 the cards in said group represent a certain kind of golf club, and means on the cards of the various groups for designating strokes that can be made with golf clubs, certain 15 cards of each group having means which indicates that the player is restricted to the use of a certain card on the following play.

8. A deck of cards, comprising a plurality of groups of cards, each group of which is provided with means for indicating that 20 the cards in said group represent a certain kind of golf club, and means on the cards of the various groups for designating strokes that can be made with golf clubs, certain 25 cards having penalties and restrictions thereon.

9. A deck of cards, comprising a plurality of separate and distinct groups of cards, the cards of each group being provided on 30 their backs with means for indicating that the cards represent a certain kind of golf club, and on their faces with means that designate distances.

10. A deck of cards, comprising a plurality of separate and distinct groups of cards, the cards of each group being provided on 35 their backs with means for indicating that the cards represent a certain kind of golf club, and on their faces with means that designates distances, certain of the cards of each group also being provided on their 40 faces with means designating penalties and also the particular card which has to be played on the following turn of the player who played the card.

11. A deck of cards divided into a plurality of groups, the cards of each group being provided on their backs with a word, character, or symbol that designates a particular kind of golf club, means on the faces 45 of the cards that designate different distances, and means on the faces of certain cards of each group that designate distance penalties which reduce the value of the card.

12. A deck of cards divided into a plurality of groups, the cards of each group being 50 provided on their backs with a word, character, or symbol that designates a particular kind of golf club, means on the faces of the cards that designate different distances, and means on the faces of certain cards of 55 each group that designate distance penalties which reduce the value of the card, certain of the cards of each group also having words or characters on the face of same that restrict the player of the card to the use of a certain card on his succeeding turn.

In testimony whereof I hereunto affix my signature in the presence of two witnesses, this sixteenth day of June 1914.
